UNITED STATES PATENT OFFICE.

EMIL WEINHEIM, OF NEW YORK, N. Y.

REINFORCED LEATHER AND PROCESS OF MANUFACTURING THE SAME.

965,261.

Specification of Letters Patent. Patented July 26, 1910.

Application filed August 7, 1909. Serial No. 511,696.

To all whom it may concern:

Be it known that I, EMIL WEINHEIM, a citizen of the United States, and a resident of the borough of Manhattan, county, city, 5 and State of New York, have invented certain new and useful Improvements in Reinforced Leather and the Process of Manufacturing Same, as set forth in the following specification.

10 This invention relates generically to the improvement of tanned hides of an inferior quality, it being understood that the expression "hide" is used to designate both the whole hide or any portion thereof.

15 As is well known, animal leather varies in character and particularly in thickness according to the locality on the animal from which it was taken. The variation in the thickness in the leather in some hides from 20 one locality to another is so great that but a comparatively small portion of a natural hide is of uniform thickness and suitable for commercial use where a uniform minimum thickness is necessary. Under these conditions the entire remaining portions of the 25 hide are waste so far as that particular industry, requiring a uniform minimum thickness for the leather, is concerned.

It is an object of the invention to build up 30 such portions of a hide which are below the desired minimum thickness and create artificially a hide of the desired uniform minimum thickness. To this end a suitable closely adherent patina, which closely approximates 35 leather in its composition, is employed. This patina is applied to the flesh side of the tanned hide in a viscous state, caused to incorporate itself thereon, is distributed over the surface so that the combined thickness of 40 the patina and natural hide becomes uniform, whereupon the patina is insolubilized or solidified in a suitable manner.

In some arts a fabric lining is usually 45 employed as a covering for the flesh side of leather which leather, nevertheless, as explained above, must have a uniform minimum thickness itself.

It is also an object of the invention to 50 combine a natural tanned hide, originally of varying thickness throughout its extent, with a fabric backing and an intermediate filling of a suitable patina so that the combined thickness of natural hide, patina and fabric shall be of a uniform minimum thickness throughout. In connection with this 55 object of the invention, it is to be borne in

mind that the combined thickness of the patina and natural hide are caused to correspond to the desired uniform minimum thickness for the leather, the fabric backing 60 being itself of uniform thickness throughout.

To this latter end the invention contemplates the application and incorporation of a suitable patina with the flesh side of the hide. The word "patina" is used in this 65 specification the same as in the trade to designate a viscous substance to be applied to a surface. It is distributed in any suitable manner to achieve the generic object of the invention, namely, to effect the uniform 70 thickness of a hide. The patina may be applied directly to the flesh side of the hide and distributed over it. The fabric backing may then be applied to the patinated surface of the hide or the patina may be first applied to the fabric backing and the hide subsequently applied to the patinated surface 75 of the fabric backing, flesh side down, and then the combined fabric treated in a suitable manner, as by rollers, to distribute the 80 intermediate patina in a manner to effect combined uniform thickness.

The above and further objects of the invention will be set forth more particularly in the following claims and will be clear 85 from the following specification, which should be read in connection with the accompanying drawings, forming part of this application, in which like characters designate corresponding parts, and in which,— 90

Figure 1 is a diagrammatic representation in vertical elevation and partly in section of apparatus for carrying out the process; Fig. 2 is an exaggerated section through a portion of the natural tanned hide to be 95 treated; Fig. 3 is a view corresponding to Fig. 2 showing the hide lined and built up into one of uniform thickness; Fig. 4 is a diagrammatic view corresponding to Fig. 1 but showing modified apparatus for 100 rendering hides uniform in thickness without lining; Fig. 5 is a plan view of a section of the carrier and hide affixed thereto; Fig. 6 is an exaggerated sectional view through line VI—VI of Fig. 5; and Fig. 7 105 is a view corresponding to Fig. 6 but showing the finished hide alone, built up into leather of uniform cross section.

The patina to be employed may be preferably a leatherfying composition as follows:— 110
1. Suitable coloring matters, preferably mineral. 2. Viscous animal parts, such as

2
bone glue, glutin and other glutinous matter of animal origin. 3. Vegetable oils, such as palm oil, olive oil and others. 4. Hydro-carbons, such as paraffin, vaseline, 5 bitumen or others. 5. Metallic salts, such as hydrated oxid of zinc, potassium, lead and aluminum. 6. Animal fats, such as tallow, suet and others. 7. Suitable saponifying agents, such as sodium and potassium al- 10 kalies.

The various ingredients enumerated may be employed in various proportions easily determined by experiment but their various proportions should be such as to render the 15 resultant composition sufficiently viscous, at approximately 70° to 80° Fahrenheit, for it to be spread upon the surface to be patinated. Selections from the first six sets of 20 the ingredients may be kneaded and mixed together in a suitable vessel under the influence of heat and then one of the seventh set of ingredients should be added and thoroughly mixed.

For proceeding with the process with 25 apparatus as shown in Fig. 1, the trough 1 is maintained full of the desired patina, which may be kept at the desired viscosity by means of heat applied in any suitable and well known manner. The trough 2 is 30 kept full of a solution of an insolubilizing agent, such as dichromate of potassium. A strip of suitable artificial fabric 3 of uniform thickness, which may be of any desired character, but preferably a textile, 35 such as cotton drill, is unwound from the roll indicated; and is threaded through the guide rolls 4, then between the doctor roll 5, immersed in the dichromate solution, and the opposing guide roll 6. The strip of 40 fabric then passes over the steam heated roll 7 and between it and the neighboring steam heated roll 8. The strip then passes about the power driven drum 9 between it and the adjustable doctor roll 10 suitably 45 immersed in the patina of trough 1. The strip then passes by the reciprocating brush 11 which may be power driven and adjusted relatively to the surface of the strip 3 in any desired manner as, for instance, in that 50 manner apparent from mechanism illustrated. The reciprocation of the brush 11 is shown to be parallel to the length of the strip. The strip then passes between shields 12 and 13 to one or more pairs of 55 adjustably mounted power driven compression rolls 14 and 15. The pairs of rolls 14 may be adjusted by means of screws 16 to the desired uniform distance apart while it may be desirable to adjust the pair of 60 rolls 15 nearer together by means of the similar adjusting screws 17. At this point in the process an attendant, who may stand on the platform 18, feeds a hide 19, flesh side 20 down, upon the patina 21 on strip 65 3. After passing beneath the rollers 14 and

15 the strip is carried by an endless carrier 22, preferably driven at a speed slightly in excess of the peripheral speed of the rollers 14 and 15, to bars 23 carried by an intermittently advancing carrier 24. The strip 70 of fabric 3 with its attached hides is caused to drop down in festoons over each end cross bar 23 so that each festoon carries one or more pairs of hides as indicated. Additional rods 23 may be inserted as the fabric 75 is delivered, whereupon they are carried to a drying room of any suitable character.

A section of a hide 19 to be treated is clearly shown in Fig. 2. The irregular flesh side 21 is also clearly shown as well as the 80 smooth regular hair side surface 25.

The strip 3 in passing over the doctor roll 5, is uniformly coated with dichromate solution. The passage of the strip over the heated rolls 7 and 8, together with its passage through the air, dries out the water from the applied dichromate solution effecting a uniform crystalline deposit of dichromate of potassium in and about the surface fibers of the fabric 3. It is desir- 90 able to maintain the drum 9 at just a sufficient temperature to maintain the desired viscosity for the patina applied by the doctor roll 10. This patina is spread uni- 95 formly over the dichromatized surface of strip 3, is incorporated with the dichromate and remains there in a more or less viscous mass until after passing through the compression rolls 14 and 15. The compression 100 rolls, which are maintained perfectly parallel one to another, first grip the inserted edge of hide 19 which is held back by the attendant and suitably stretched. These rolls may preferably be heated to a suitable temperature upward of 80° Fahrenheit and 105 are effective in distributing the patina previously applied to the fabric strip 3 so as to fill up the irregular portions of the flesh side surface 20 of hide 19. This patina, 110 therefore, forms an irregular layer 21 on the surface 20 and on the fabric surface 26 so that the hair side 25 of the hide is parallel to the outer surface 27 of the fabric 3 and the combined fabric is of the desired uniform minimum thickness throughout and 115 is a firmly secured composite fabric. The heat applied by the compression rolls 14 and 15 and also the exposure to light when traversing the carrier 22 and when suspended in festoons on the carrier 24 causes 120 the dichromate of potassium to insolubilize the layer of patina 21 which has incorporated itself firmly in its previous soluble state with the fibrous surface 26 of the fabric 3 and the fibrous flesh side 20 of the hide 125 19. The parts are thereby cemented together in a water-proof manner. After 130 drying, this combined fabric is a permanent commercial product, it being understood that the fabric backing may be trimmed off

to approximate the contour of the natural hide. This finished product is shown in cross section in Fig. 3. So far, the process has been described as practiced to include the reinforcement of a hide by means of a fabric lining. However, as heretofore mentioned, the invention contemplates, broadly, effecting uniform thickness for a natural hide, to accomplish which it is not necessary to provide a permanently attached lining of textile fabric.

In Fig. 4 apparatus is illustrated suitable for treating a hide to effect its uniform thickness throughout. A suitable carrier, 15 which may be a strip of canvas 28 of uniform thickness may be lapped about the drums 29 and 30 and its ends secured together by lacings 31 to provide an endless carrier traveling about drums 29 and 30 20 which may be power driven in a suitable and well known manner. Hides 19 may be applied to the surface of the carrier 28, hair side down, and secured thereto in any suitable manner, as by stitchings 32. If desired the entire outside surface of the carrier 28 may have hides attached to it. After this has been accomplished the drums may be rotated to cause one of the hides to pass over the doctor roll 5 where its flesh side is coated 25 with dichromate of potassium solution. The hide is then passed over the drying rolls 7 and 8 and may be further dried by an air blast upwardly directed against it from the nozzle 33. A crystalline deposit of dichromate of potassium is obtained in this manner in and about the surface fibers of the hide. The hide is then passed over the counter rotating doctor roll 10, by means of 30 which a layer of patina is applied to it. The reciprocating brush 11 thoroughly incorporates the patina with the dichromate of potassium and with the surface fibers of 35 the hide.

It is to be understood that the doctor rolls 45 5 and 10 may both be adjusted so as to effect deposits only upon the surface of the hides and not upon the surface of the carrier 28. Furthermore the adjustment may be such as to regulate the amount of deposit effected.

50 After passing the brush 11 the carrier causes the hide to pass between power driven, parallel, compression rolls 14, the opening between which may be regulated as heretofore described by means of the screws 16. The passage of the carrier and attached 55 hide with its superposed layer of patina between the rolls 14 distributes the patina about the irregular surface 20 of the hide so as to fill up all the hollows therein and 60 makes a finished surface 34 parallel with the hair side surface 25.

It is to be understood that the parts indicated in this apparatus and numbered similarly to others in Fig. 1 are the same as 65 those of Fig. 1 so numbered. However, in

Fig. 4 there is illustrated but a single pair of rolls 14, a flat topped table 35 taking the place of one set of rolls. As previously described it is preferable to heat the rolls 14 to aid in insolubilizing the patina applied 70 to the hide. This may be continued by subsequent exposure to light and heat. After passing out of the rolls 14 the patinated hide may be stripped from the carrier 75 28 by cutting the stitches 32 and may be carried to a drying room after which it is serviceable for use in the arts.

Figs. 5 and 6 illustrate clearly the manner in which a hide is applied to the carrier 28 for the purpose of effecting its uniform 80 thickness, it being noted that the flesh side 20 is uppermost.

Fig. 7 clearly illustrates, in cross section, a hide the uniform thickness of which is effected by means of the incorporated layer 85 21 of leatherfied patina.

The composition for the patina described is described as being leatherfied after the insolubility thereof has been effected by a suitable agent such as dichromate of potassium subjected to heat and light. This composition firmly incorporates itself in and about the surface fibers of the natural leather and very nearly approximates, when insolubilized, the natural animal binder 90 holding the fibrous elements of natural leather together.

Although the advantage of incorporating the leatherfying composition with the surface to be covered while this composition is 100 soluble and in insolubilizing it thereafter is fully appreciated, it is also contemplated that a patina may be employed into which an insolubilizing agent has been mixed before (preferably a short time before) this 105 patina is applied to the surface of the coating and also that, for some purposes, an initially insoluble patina may be employed. It is further to be understood that the patinated surface 34 of the product shown in Fig. 110 7 may be recoated, varnished or otherwise treated as desired and as known in the art. Furthermore it is by no means necessary that an endless carrier 28 be employed for the purpose of creating the product shown 115 in Fig. 7. As a matter of fact a discontinuous carrier such as fabric of Fig. 1 might be employed. Also in connection with the production of the lined product shown in Fig. 3, it is to be understood that the hides 120 19 applied to the strip 3 may be first patinated on their flesh sides in accordance with the process set forth in connection with Fig. 4 or they may be first subjected only to a part of the treatment described in connection with Fig. 4, as for instance, the dichromatizing step described therein. Again, it is well understood that other modes and apparatus for carrying out the applicant's 125 invention may be possible although com- 130

plete and satisfactory methods have been described.

What is claimed and what is desired to be secured by United States Letters Patent is:—

- 5 1. The process of transforming tanned hides into leather of uniform thickness comprising, applying a closely adherent, viscous, patina of substantial body to the irregular flesh side of a hide; incorporating said patina with said surface; and finishing off the surface of the patina parallel to the hair side of the hide.
- 10 2. The process of transforming tanned hides into leather of uniform thickness comprising, dichromatizing the flesh side of the hide; applying a soluble leatherfying patina of substantial body to the dichromatized surface of the hide; incorporating said patina with said dichromatized surface; and finishing off the surface of the patina parallel to the hair side of the hide; and insolubilizing said patina *in situ* upon the flesh side of the hide.
- 15 3. The process of reinforcing and transforming tanned hides into leather of uniform thickness comprising, interposing a closely adherent viscous patina of substantial body between the flesh side of the hide and a strip of fabric; compacting the composite fabric between parallel surfaces to distribute the interposed patina throughout the depressions in the flesh side of the hide and to effect uniformity of thickness throughout the composite fabric; and solidifying the interposed patina.
- 20 4. The process of reinforcing and transforming tanned hides into leather of uniform thickness comprising, interposing a closely adherent, soluble leatherfying patina

of substantial body between the flesh side 40 of a hide and a strip of fabric after first dichromatizing one or more of the surfaces between which said patina is interposed; subjecting the composite fabric to pressure between separated parallel surfaces; and insolubilizing said interposed patina *in situ* 45 through the medium of dichromate under exposure to heat or light.

5. As an article of manufacture, the product of the process described comprising, a 50 tanned hide, the irregular flesh side of which is filled with a closely adherent patina having a finished surface parallel with the hair side of the hide.

6. As an article of manufacture, the product of the process described comprising, a 55 tanned hide the depressions in the irregular flesh side of which are filled with a closely adherent leathery composition insolubilized *in situ* and having a finished surface parallel with the hair side of said hide.

7. As an article of manufacture, the product of the process described comprising, a reinforced tanned hide of uniform thickness 65 consisting of a natural tanned hide, the depressions in the flesh side of which are filled with a closely adherent patina thoroughly incorporated therewith and with the surface of a superposed artificial fabric lining.

In witness whereof, I have signed my name to this specification, in the presence of two subscribing witnesses.

EMIL WEINHEIM.
